UNITED STATES PATENT OFFICE.

JOHN DYSON, OF DRACUT, MASSACHUSETTS, ASSIGNOR TO GEORGE M. ARRAGG, OF LAWRENCE, MASSACHUSETTS.

TRAVERSE-MOTION.

1,372,408.

Specification of Letters Patent. Patented Mar. 22, 1921.

Application filed April 19, 1920. Serial No. 372,957.

To all whom it may concern:

Be it known that I, JOHN DYSON, a citizen of Great Britain, residing at Dracut, in the county of Middlesex and State of Massachusetts, have invented certain new and useful Improvements in Traverse-Motions, of which the following is a specification.

This invention is peculiarly applicable to textile machines or frames in which there are rollers covered with leather or other similar material which deliver yarn or roving. Such rollers are especially used on spinning, twisting, and roving frames.

Particularly with wool, if the yarn or roving passes through at the same point, the leather roll would rapidly be cut and rendered useless. Therefore, on such machines there is generally what is known as a traverse motion comprising a traverse bar which extends from one side to the other of the machine, with suitable guides which cause the yarn or roving to move back and forth longitudinally of the roller. Thereby the wear is distributed and the roll is not cut as rapidly as if the wear came at one place. Such a traverse motion is generally produced by means of a cam or eccentric which, for the purpose of this description, may be regarded as substantially the same, and as the traverse motion moves back and forth there is such a dwell at the ends that the rolls are worn unevenly and frequently cut.

Especially when changing from fine to coarse work, the rolls are frequently cut, making bad work. To partly overcome this it is customary to increase the pressure on the rolls, which requires more power to drive them. Such pressure tends to flatten out irregularities but is objectionable on account of the extra power required.

The purpose of this invention is to more evenly distribute the wear by shifting the turning points of the traverse motion so that such turning points will be distributed along the face of the roll.

I believe that this invention is not only applicable to textile machines, but is a new mechanical motion, and I therefore claim it as such.

In the drawings, Figure 1 is an elevation of my device applied to the traverse motion cam in common use on a spinning frame, showing the parts in one position.

Fig. 2 is a diagram showing the manner

in which the traverse shifts as the eccentric follower revolves.

Fig. 3 shows another position of the parts.

Fig. 4 shows a modification of the cam or eccentric and a slight modification of the follower.

Fig. 5 shows another position of the cam and follower shown in Figs. 1 and 3.

In the drawings, A represents the frame of a textile machine of the spinning frame type, and B is a bracket attached thereto by bolts or rivets 10. The bearing C is attached to bracket B by means of bolts or rivets 11 and supports a driving shaft D, which is driven by means of a gear G and has fixed to it the cam F shown as rigid thereon by means of a spline 12. R, R are the delivery rolls.

The bearing for shaft D is a fixed bearing on the frame. Instead of the usual depression in cam F, I provide a notch with an easy slope 20 and a sharp slope 21 so located that the sharp slope 21 travels forward and will engage the follower in a manner to be described.

H is the traverse bar of the traverse motion of well known form, and to this is adjustably attached the bracket K having a slot 13 through which passes the bolt 14 for adjustment. The spring S connected to the frame A at 17 and to bracket K at 16 tends to pull the traverse motion toward the right when permitted.

Bracket K has a slot 15 in which is a stud L having a flattened portion 24 and a head 25 held adjustably in position by a nut 27.

Inside the head 25 and revoluble on stud L is the follower M, which is substantially an eccentric with a plurality of teeth 22, 22, having concave portions 23 between. This eccentric follower is revoluble on the pivot, which is stud L, movable with the traverse motion, and is kept in engagement with the cam or eccentric F by the action of spring S.

As the cam F revolves, it forces the follower and traverse motion away up to the point of the cam and allows it to recede as the spring pulls it back to the notch 20, 21. When the notch comes around, as shown in Fig. 5, it engages a tooth 22 and moves the eccentric follower one tooth. The operation is repeated as the cam revolves the follower.

In the drawings, the follower is shown as

having eight teeth, and it will be seen that for each eight revolutions of the cam the follower is revolved once. The result is that the traverse motion moves on the rolls, as shown between the points 30 and the points 31 in Fig. 2.

In Fig. 4, I show in place of a heart-shaped cam the eccentric P carried by the fixed pivot or shaft D and having a notch 40. The throw of this cam is shown as less than F.

I also show the movable pivot 26 for the follower T as smaller and nearer to one edge, so that its throw will be larger than that of follower M.

It will readily be understood that by changing the throw of the cam and follower different lines of wear on the rolls can be established. This can be done by removing the cam or follower, or both, and replacing one, or both, by one of a different size or shape.

In Fig. 2, 7 represents a traverse guide carried by traverse rod H of a traverse motion. The zigzag line 30, 31 indicates the shifting motion of traverse eye 7. The length of each line 30, 31 is determined mainly by the throw of cam F, and the general curve of the zigzag line by the throw of the follower. It will be understood that the motion of the rolls is much more rapid than that of the traverse motion, so that the zigzag line in

Fig. 2 is merely diagrammatic. As a matter of fact, the rolls R, R revolve in many cases several times while the traverse motion is moving once back and forth. 35

I claim:

1. The combination with a spinning machine having a frame, rolls and a traverse motion including a traverse bar, of a cam 40 having a notch with an easy slope and a sharp slope so located that the sharp slope travels forward, said cam being revoluble in a fixed bearing on the frame, with a pivot movable with the traverse bar, a follower 45 eccentrically revoluble on said pivot and having its periphery formed of a plurality of teeth of such form as to be successively engaged and turned by the sharp slope of the notch in the cam, and a spring between 50 the frame and traverse bar to keep the cam and follower in engagement.

2. In a mechanical motion, the combination of a revoluble eccentric having a notch with an easy slope and a sharp slope so located that the sharp slope moves forward, with another eccentric in contact therewith having a plurality of teeth adapted to engage the notch in the first named eccentric, and means to keep the eccentrics in engagement. 55

In testimony whereof I have affixed my signature.

JOHN DYSON.
